RADIO RELAYING SYSTEM

Clarence W. Hansell, Port Jefferson, N. Y., assignor to Radio Corporation of America, a corporation of Delaware

Application January 7, 1943, Serial No. 471,587

8 Claims.

(Cl. 250—15)

This invention relates to improvements in radio relaying systems.

In setting up a long series of standardized radio relay stations, such as might be used for television for example, there would normally be used standardized masts or towers of the same dimensions at all repeater stations for both the transmitting and receiving antennas. Since the transmission lines between the repeater apparatus (customarily located near the ground) and the transmitting and receiving antennas would tend to have the same lengths, there would be, in consequence thereof, a tendency for addition of reflection effects upon the useful modulation.

The primary object of the present invention is to prevent cumulative distortions in repeater stations of a radio relay system brought about by wave reflections on transmission lines at these stations.

It is proposed to accomplish the results of the invention by deliberately varying the lengths of the transmission lines carrying radio frequency currents at the different stations, in order to obtain different time delays for reflected waves in a manner to avoid adding up reflection effects and thus avoid producing multiple images or bad distortion. This can be done by making the transmission lines at one station differ in length from those at another station, and also, preferably, making the lines at the same repeater station differ in length from each other.

Thus, if the transmission line at one repeater station is made to be one-quarter wave, or an odd number of quarter waves, different from the corresponding transmission line at another station, then if both lines were subject to equal reflection effects the resulting secondary images or distortions would be of reverse polarity in the two lines and would tend to cancel out in the system as a whole. At the same time, if at one station there is reflection due to low impedance termination and at the next corresponding station there is reflection due to a high impedance termination, then we automatically tend to get a cancellation of secondary images. Where all sorts of reflections may exist, it is possible to minimize the distortions due to reflection by juggling the lengths of individual transmission lines over a range of one-quarter wave length of the carrier current. In practice it is found that the reflections are not sufficiently constant to permit distortion balancing by this small range of transmission line length variation, then it is proposed to make much greater differences in transmission line

lengths in order that a large range of time delays may be produced due to reflections, as a consequence of which there will not be an amplitude addition of the reflected modulation components but instead a series of much smaller distortions scattered out with respect to time which will consequently be much less noticeable.

A better understanding of the invention may be had from a reading of the following description which is accompanied by drawings wherein Figs. 1 and 2 illustrate how the principles of the invention can be applied to two different types of repeater stations in a radio relaying system, and Figs. 3 and 4 illustrate the principles of the invention applied to a plurality of repeater stations in a radio relaying system.

Referring to Fig. 1 in more detail, there is shown one repeater station typical of a group of similar repeater stations of a radio relaying system. This repeater station comprises a pair of similar masts 1 and 2 for respectively supporting receiving antenna R and transmitting antenna T at locations highly elevated with respect to ground. The receiving and transmitting antennas R and T are merely illustrative of any suitable equipment for receiving and radiating waves, and are shown herein conventionally as including a parabolic antenna with the dipole arrangement at or near the focus of the parabola. The receiving antenna R on the top of mast 1 is connected by means of transmission line A to the input of repeater apparatus M which is located at or near the ground. The output of repeater apparatus M is connected by means of line B to the transmitting antenna T at the top of mast 2. Repeater apparatus M may constitute any suitable electron discharge device amplifying equipment. In practice, it is almost impossible to obtain a perfect impedance match between the line A and the terminal apparatus constituting the receiving antenna and the input of the repeater equipment M. This is also the case with regard to the line B and its terminal apparatus constituting the transmitting antenna and the output of the repeater M. Due to the impedance mismatch between lines A and B and their respective terminal apparatus, there are reflections on the lines A and B which will (after time delays determined by the length of the line) either add to or oppose the incoming and/or outgoing main signal waves. Thus, in line A the mismatch between the impedance of this line and the receiving antenna and the repeater will cause delayed reflected waves of incoming energy to occur on the line A which may add to or oppose

the main incoming wave. Similarly, the mismatch between the impedance of line B and the terminal equipment comprising transmitting antenna T and the repeater apparatus M will cause delayed reflected waves of outgoing energy to occur on line B which may add to or oppose the main outgoing wave. The reflections in both lines A and B may add or oppose each other insofar as the signal modulation distortion is concerned. In television, such distortion produces multiple or ghost images. These distortion effects can be quite pronounced if all repeater or relay stations are standardized as to tower lengths and locations of similar pieces of equipments and all these pieces of equipments are made to be alike. There thus exists the probability in the case of completely standardized equipment at all stations that the reflections at all the repeater stations may cause additive distortions.

In accordance with the present invention, the lengths of lines A and B at any one repeater station are made different from the same or similar lines at another repeater station, and this difference is preferably electrically one-quarter wavelength (or an odd number of quarter wavelengths) at the operating frequency. Note Fig. 3. It is also preferred that the line A be made to differ in length from the line B at the same repeater station also by one-quarter wavelength (or an odd number of quarter wavelengths) electrically at the operating frequency. This odd number of electrical quarter wavelengths difference reverses the polarity of the distortion and thus it is possible for the distortion produced at the same station to balance out, and the distortions at adjacent stations also to balance out.

If desired, the lines A and B of each relay station could be made to differ electrically by one-eighth wavelength, or an integral number of half wavelengths plus or minus one-eighth wavelength, in which case there cannot be either addition or opposition of the distortions produced by lines A and B of the same station.

Fig. 2 shows a modified arrangement of a type of repeater station wherein the receiving antenna R is connected by means of transmission line C to receiving and demodulating means F located at or near the ground. Similarly, the transmitting antenna T located at the top of another and similar tower is connected by line D to transmitting and re-modulating equipment G also located at or near the ground. The output of the equipment F is connected to the input of the equipment G by way of a video or modulation frequency cable E which may be one-quarter to one-half mile in length. Thus, lines C and D carry radio frequency currents, while video cable E carries a much lower frequency current. Alternatively, in a manner known in the art, the high frequency energy received by antenna R and delivered to the receiver and demodulator over line C may be changed by a suitable local heterodyne or beating oscillator to lower frequency currents which may then be transmitted over the cable E to the transmitting and remodulating equipment G where another local beating oscillator and suitable single side band filters produce radio frequency currents for transmission over the line D to the transmitting antenna T.

In order to prevent additive distortions in the case of Fig. 2, it is desired that the video or lower frequency cables E at the different repeater stations be of different lengths. It should here be noted that there is no continuous radio frequency

path between the receiving and transmitting antennas of the same station due to this low frequency link. It is preferred that this low frequency cable be as variable in length from one station to the other as economically feasible, and that lines C and D at each repeater station should differ electrically from each other by one-eighth wavelength (or an integral number of half wavelengths plus or minus one-eighth wavelength) at the operating frequency. Also, that the mean length of the lines C and D at any one repeater station should differ electrically by one-eighth wavelength or by an integral number of half wavelengths plus or minus one eighth wavelength thereof from the mean length of the same lines at any other repeater station in the radio relay chain. This is shown in Fig. 4.

Although separate towers have been shown for supporting transmitting and receiving antennas, it should be understood that a single tower may be used in some cases to support both.

What is claimed is:

1. A radio repeater station comprising a receiving energy collector and a separate transmitting energy radiator, means for supporting said energy collector and said radiator at a distance above ground, electron discharge device translation circuits located at or near the ground, and radio frequency lines which differ electrically by one-quarter wavelength or an odd number of quarter wavelengths at the operating radio frequency connecting said energy collector and said radiator to different parts of said translation circuits.

2. A radio repeater station comprising a receiving energy collector and a separate transmitting element, means for supporting said energy collector and said transmitting element at a distance above ground, electron discharge device translation circuits located at or near the ground, and radio frequency lines which differ electrically by one-eighth wavelength, or by an integral number of half wavelengths plus or minus one eighth wavelength, at the operating radio frequency connecting said energy collector and said transmitting element to different parts of said translation circuits.

3. A radio repeater station comprising a receiving energy collector and a transmitting radiator spaced therefrom, individual masts supporting said energy collector and said radiator at an appreciable distance above ground, electron discharge device translation apparatus located at or near the ground and having input and output circuits, and radio frequency lines of different electrical lengths connecting said receiving energy collector and said transmitting radiator to said input and output circuits, respectively, the lengths of said lines being such that reflection effects occurring in one line are substantially cancelled by reflection effects occurring in the other line.

4. A radio repeater station comprising a receiving energy collector and a transmitting radiator spaced therefrom and effective in a different direction, individual masts supporting said energy collector and said radiator, an electron discharge device modulator circuit near the foot of the mast supporting said receiving energy collector, an electron discharge device remodulator device near the foot of the other mast, radio frequency carrying lines of different electrical lengths connecting the receiving collector and transmitting radiator to the input of the demodulator and the

output of the re-modulator, respectively, and a cable connecting together the output of said demodulator and the input of said re-modulator, said cable carrying currents of lower frequency than the frequency of the currents carried by said radio frequency lines.

5. In a radio relaying system, a plurality of radio repeater stations, each of said repeater stations having a receiving energy collector and a transmitting radiator each effective in a different direction, individual masts supporting said energy collector and said radiator, an electron discharge device demodulator circuit near the foot of the mast supporting said receiving energy collector, an electron discharge device re-modulator device near the foot of the other mast, radio frequency carrying lines of different electrical lengths connecting the receiving collector and transmitting radiator to the input of the demodulator and the output of the re-modulator, respectively, and a cable connecting together the output of said demodulator and the input of said re-modulator, the mean length of the radio frequency carrying lines at one repeater station differing from the mean length of the radio frequency carrying lines at another repeater station by an integral number of half waves plus or minus one-eighth wavelength.

6. In a radio relaying system, a pair of radio repeater stations, each repeater station having a receiving energy collector and a transmitting energy radiator, means for supporting said energy collector and said radiator at an appreciable

distance above ground, electron discharge device translation circuits located at or near the ground, and radio frequency lines connecting said energy collector and said radiator to said translation circuits, the mean length of the lines at one repeater station differing electrically from the mean length of the lines at the other repeater station by approximately an odd number of quarter wavelengths, including one-quarter wavelength.

10. 7. In a radio relaying system, a pair of radio repeater stations, each having a receiving energy collector and a transmitting radiator, means for supporting said energy collector and said radiator at the same appreciable distance above ground, electron discharge device translation circuits located at or near the ground, and radio frequency lines of different electrical lengths connecting said energy collector and said radiator to said translation circuits, the mean length of the lines at one repeater station differing electrically from the mean length of the lines at the other repeater station.

15. 8. In a series of radio relaying stations each having transmitting and receiving antennas individually connected to vacuum tube translating apparatus by means of transmission lines, the method of reducing signal distortions due to reflections on transmission lines which comprises 20 making different adjustments of the lengths of said lines at the several stations to prevent addition of distortions.
